United States Patent Office

Des. 198,462
Patented June 16, 1964

198,462

TOY BATTLESHIP

Roy Fitzgerald Constan, Staten Island, N.Y., assignor to De Luxe Reading Corp., Elizabeth, N.J., a corporation of New Jersey

Filed Nov. 12, 1963, Ser. No. 77,347

Term of patent 14 years

(Cl. D34—15)

FIG. 1 is a view in perspective from a point off the port bow showing the left or port side of the design, and,

FIG. 2 is a view in perspective from a point off the starboard quarter showing the right or starboard side of the design.

The dominant features of my design reside in the portions shown in full lines.

The broken lines indicating planes and missiles are for illustrative purposes only.

I claim:

The ornamental design for a toy battleship, as shown and described.
